UNITED STATES PATENT OFFICE.

GRANT HOLMES, OF DANVILLE, ILLINOIS, ASSIGNOR TO THE MARION STEAM SHOVEL COMPANY, OF MARION, OHIO, A CORPORATION OF OHIO.

BOOM.

Application filed April 28, 1924. Serial No. 709,428.

To all whom it may concern:

Be it known that I, GRANT HOLMES, a citizen of the United States, residing at Danville, in the county of Vermilion and 5 State of Illinois, have invented certain new and useful Improvements in Booms, of which the following is a specification, reference being had therein to the accompanying drawing.

10 This invention relates to booms and is in the nature of an improvement on the boom structure shown and described in application for patent filed by me July 30, 1923, Serial No. 654,568. Rotary power shovels as constructed in the past have for the most part 15 comprised a rotary frame on which the boom was mounted, the foot of the boom usually resting in a socket or between ears at the front end of the frame and extending upward and forward at an angle of about forty-five degrees. The boom is held in this position by suspension from the point thereof by means of cables or hog rods extending from the boom to a gantry, or 20 25 A-frame, mounted on the revolving frame and braced or stiffened by means of a bridge, which bridge also provides a high point for connecting the cables or hog rods. The boom itself is usually heavier, or of greater 30 size, near the center thereof and the upper and lower sides or edges thereof converge 35 forwardly and rearwardly. The shipper shaft and crowding engine are mounted on this heavier portion of the boom and the dipper handle extends through the boom adjacent to the shipper shaft. When a 40 machine of this character is not working and the dipper is resting on the ground the boom is subject to certain strains, the 45 under side of the boom being under tension and the upper side of the boom being in compression. When the dipper is raised off the ground these strains are proportionately increased, it being understood that 50 in the larger types of shovels these dippers are of large size and even when empty impose a heavy load on the boom. When the dipper is crowded into the face of the bank, upon which it is working, a backward thrust 55 is exerted through the dipper handle and shipper shaft and this thrust serves to reverse the strains imposed upon the boom, the lower side of the boom being placed under compression and the upper side of

the boom being placed under tension. After 55 the dipper has finished its cut and the weight of the loaded dipper imposed on the boom the strains are again reversed, bringing the lower side of the boom under tension and the upper side under compression. 60 It will be understood that in the operation of the shovel this reversal of the strains takes place at frequent intervals and is highly destructive of the boom. As has been 65 stated most booms of this character are heavier adjacent to the shipper shaft, but the portion of the boom between the shipper shaft and the point is subjected to these constantly reversing strains with the result that it is gradually weakened to the breaking 70 point. Further, the swinging of the loaded dipper imposes a very severe twisting strain on the lower or foot portion of the boom, which is smaller in section, usually about one-third of the distance from 75 the foot of the boom to the shipper shaft, and this strain gradually weakens this portion of the boom to the breaking point. These strains are present in all booms of 80 this character but they become more pronounced in the larger size machines and it has been found impractical to increase the size and strength of a boom of this kind sufficiently to overcome the destructive action 85 of the strains upon the boom. 85

One object of the present invention is to provide a boom of great strength which will be compact in its arrangement and of a relatively light weight, as compared with 90 its strength. 90

A further object of the invention is to provide a boom of this character the upper lateral edges of which will each constitute a straight line from the point of the boom to the rear end of the supporting structure 95 or platform. 95

A further object of the invention is to provide such a boom structure in which the boom and the frame members will be rigidly braced and reinforced against the strains 100 to which the structure is subjected in operation. 100

Other objects of the invention will appear as the device is described in detail.

In the accompanying drawings Fig. 1 is a 105 side elevation of a boom structure embodying my invention, showing the same as applied to a power shovel of the rotary type;

Fig. 2 is a longitudinal section through the frame and a portion of the boom proper, on the line 2—2 of Fig. 5; Fig. 3 is a longitudinal section through one of the side members of the frame and a portion of the boom, on the line 3—3 of Fig. 5; Fig. 4 is a transverse section taken on the line 4—4 of Fig. 1; Fig. 5 is a top plan view of the boom structure; Fig. 6 is a bottom plan view of the same; Fig. 7 is a section taken on the line 7—7 of Fig. 1; Fig. 8 is a rear elevation of the boom structure; Fig. 9 is a section taken on the line 9—9 of Fig. 1; Fig. 10 is a section taken on the line 10—10 of Fig. 1; Fig. 11 is a detail view of the horizontal reinforcing plates; Fig. 12 is a detail view of one of the side members of the frame portion of the structure; Fig. 13 is a side elevation of a portion of one of the plates of the boom portion of the structure; and Fig. 14 is a detail elevation of the vertical reinforcing plates.

In these drawings I have illustrated one embodiment of my invention and have shown the same as applied to a rotary power shovel but it will be understood that the invention may take various forms and that the boom may be used in connection with mechanisms of various kinds without departing from the spirit of the invention.

In the particular embodiment here shown the excavating machine or power shovel comprises a base or truck frame 1 on which a platform or supporting frame 2 is mounted for rotation about a vertical axis. This revolving platform carries the boom structure, the power plant and the operating and controlling mechanism. The boom structure as a whole comprises two parts; a frame portion, consisting of side members mounted along the lateral edges of the revolving platform 2, and a boom portion supported at the forward end of the platform, extending upwardly and forwardly therefrom and rigidly secured to the frame portion so that the two parts constitute a single structure. The side members of the frame portion of the boom structure may be constructed in various ways but I prefer that the construction should be of plates as described in the above mentioned application. I have therefore shown each side member of the frame portion of the boom structure as comprising a plate 3 which is substantially triangular in form and is mounted at its lower edge along or adjacent to the lateral edge of the platform, the lower edge of the plate being preferably parallel with the adjacent edge of the platform. The plate may consist of a single sheet of metal but because of its size it will ordinarily be made up of a number of sheets riveted one to the other to form a single plate or structure. The inclined edge of the triangular plate extends upwardly from the rear end of the platform to a point

above the forward end of the platform and the plate is tilted inwardly so that this upper inclined edge will overhang the platform. The upper edge of the plate being inclined and the plate as a whole being tilted it will be apparent that the upper inclined edge of the plate will extend obliquely to the edge of the platform. This plate is suitably reinforced or braced and, as here shown, a series of bunkers or brace plates 4 extend transversely to the side plate 3 and are rigidly secured thereto at their outer edges, as by means of angle irons. The inner edges of the base plates are reinforced by angle irons 5 rigidly secured thereto. The lower ends of the plate 4 and angle irons 5 are secured to the platform 2. A top plate 6 is supported on the upper edge of the side plate 3 and extends across the brace plates or bunkers 4, this top plate being secured to the upper edge of the side plate and to the upper inner corners of the brace plates by means of angle irons 7. Extending transversely between the two side members of the frame portion of the structure and preferably arranged at approximately the level of the roof of the cab is a horizontal member here shown as a plate 8 rigidly secured at its edges to the frame members and serving to tie these members together and brace them one against the other. Arranged at the forward ends of each of the side members and rigidly secured to the forward edges of the respective plates 3 are two upright plates 9 the inner edges of which are substantially parallel one with the other and are spaced apart to receive between them portions of the boom as will hereinafter appear. The upper edges of the upright plates 9 are rigidly secured to the forward edge of the horizontal plate 8. In addition to its main function of a reinforcing and bracing member the plate 8 may also serve as the roof for the forward portion of the cab, the side members 3 forming in part the side walls of the cab, the rear portion of which may be built onto the rear inclined portion of these side members, as shown in dotted lines at 10 on Fig. 1. Further this plate 8 provides a work platform above the operating mechanism.

The boom portion of the structure may be supported at its lower rear end upon the platform 2 and extends upwardly and forwardly therefrom, the upper and lower edges converging toward the point of the boom and the lateral edges of the boom also converging toward the point of the boom, so as to provide a tapered boom structure the lines of which will be straight. This boom structure may take various forms of construction but following out the plate construction of the frame portion of the structure I have formed the boom of two upright plates 11 arranged parallel one with

the other and having their upper and lower edges tapered toward the point of the boom and spaced a relatively short distance one from the other, thus providing a space 5 through which the dipper handle 12 may extend. These upright plates are connected one to the other by inclined plates 13, 14 and 15, to brace them one against the other and the plates 14 and 15 are so arranged as to 10 provide a suitable space for the operation of the dipper handle. The lower portions of the rear ends of the plates 11 extend between the two upright plates 9 and are rigidly secured thereto, the lower edges of the plates 11, as shown at 16, may, if desired, rest upon 15 the forward portion of the platform 2. Rigidly secured to the rear edges of the plates 11, above the plates 9, is a transverse upright plate 17 which extends between and is 20 rigidly secured to the side members and to the horizontal plate 8. The upright plate 17 is arranged in line with the plates 9 and the three plates form in effect a single upright member which is secured at its lateral edges 25 to the side members 3 and to which the rear ends of the parallel boom members 11 are secured. To the outer sides of each of the boom plates 11 is secured a horizontal plate 18, which plates are arranged substantially 30 in line with the horizontal plate 8 and are rigidly secured at their rear edges to the upright plates 9 and 17. These horizontal plates 18 are substantially rectangular in shape and terminate at the lower edge of the boom plates some distance in front of the 35 side frame members 3. Arranged between the boom plates 11 and in line with the plates 18 is a plate 29 which is rigidly secured at its lateral edges to the respective boom plates. The boom plates are reinforced or 40 braced by a series of outwardly extending transverse bunkers or brace plates 19 rigidly secured at their inner edges to the respective boom plates, as by means of angle irons 20, and reinforced at their outer edges by angle irons 21. Extending across the upper edges of the boom plates is a top plate 22 which is rigidly secured to the upper 45 edges of both boom plates and extends laterally beyond the same to the edges of the brace plates 19 to which it is secured by means of angle irons, or in any other suitable manner. This top plate is arranged in the same plane with and forms a continuation 50 of the top plate 6 of the side members, so that these top plates constitute in effect a single top plate extending from the point of the boom to the rear end of the platform and bifurcated at its rear end to conform 55 to the arrangement of the side members. It is also provided with openings 23 and 24 to permit the passage of the dipper handle and to receive the sheaves at the point of the boom. Rigidly secured to the lower edges 60 of the boom plates and extending outwardly to the edges of the brace plates 19 are bottom plates 25. Arranged in the triangular space formed between the plates 9, 18 and 25, on each side of the boom plates, are triangular plates 26 which are rigidly secured 70 at their upper edges to the respective boom plates along the inner edges of the horizontal plates 18 and are rigidly secured at their lower edges to the bottom plates 25, and at their rear edges to the upright plates 9. 75 The lower edges of these triangular plates 26 are arranged substantially parallel with but spaced some distance from the outer edges of the bottom plates 25. Consequently the rear edges of the plates 26 extend diagonally to the plates 9. It will be noted that the reinforcing plates or bunkers 19 at the rear end of the boom are secured at their inner edges of the triangular plates 26 and are spaced some distance from the boom members 11. Further, I have here shown the bottom plates 25 under this portion of the boom as of a width corresponding to the width of the bunker plates 19, thus leaving 80 a space between the bottom plates 25 and the boom plates. It will be noted that the upper edges of the side members 3 are in line with the outer upper edges of the boom so that the lateral edges of the top plates 6 and 22, which follow the edges of the frame plates and the boom, constitute straight lines extending from the point of the boom to the rear end of the platform 2. The lower lateral edges of the boom form 85 straight lines from the point of the boom to the forward end of the platform. The frame members and boom members are rigidly connected one to the other so as to form a unitary structure which is rigidly braced, by means of the various plates secured thereto, 90 against the strains to which the boom is subjected in service. The lower edge of the boom is preferably pivotally connected to the forward end of the platform or the frame portion of the structure. This pivotal connection is primarily for the purpose of facilitating the assembly of the boom structure in the field. It is thus possible to 95 assemble the boom portion of the structure in a horizontal position, upon suitable supporting structures, pivotally connect the same to the frame portion of the structure and by then attaching to the point of the boom cables leading to the hoisting mechanism on the platform the boom can be hoisted into its normal position and rigidly secured in that position and when so arranged the weight and thrust of the boom will come 100 upon the platform itself and not upon the hinges. As here shown, I have arranged a hinge 27 between the lower edges of the boom plates 11 and the front edge of the platform 2 and have arranged other hinges 110 115 120 125 130 between the outer portions of the boom and the platform. The intermediate hinge 125

27 not only establishes a pivotal connection between the boom plates and the platform but when the boom structure has been assembled with the parts in their normal positions this hinge forms a firm connection between the lower corners of the boom plates and the platform. As here shown the hinge 27 comprises a hinge member 30 rigidly secured to the front end of the platform and a 10 second hinge member 31 connected with the hinge member 30 by a hinge pin 32. The hinge member 31 is preferably in the form of a casting arranged to fit between the two boom plates 11 and having upright portions 15 or flanges 33 to which the boom plates are rigidly secured. This hinge member is so shaped and arranged that when the boom is in its elevated position the hinge member will rest upon the platform 2. If desired, 20 the member 31 may be provided on each side with a shoulder 34 on which the edges of the boom plates rest.

The arrangement of the horizontal and vertical transverse reinforcing plates is such 25 as to impart to the structure a high degree of rigidity and to firmly brace the same against the strains to which it is subjected in the normal operation of the machine. It will be noted that the group of horizontal 30 plates and the group of vertical plates each constitutes in effect a single member or plate the two members being arranged in intersecting planes. The upright or vertical plates 9 and 17 constitute in effect a single 35 plate or member rigidly secured at its lateral edges to the frame members 3 and to which the rear edges or boom members 11 are rigidly secured. The horizontal plates 18 and 29 also constitute in effect a single 40 plate or member which is rigidly secured to the side members and to the boom members. Either the horizontal plate or the vertical plate may be divided into two parts at the 45 line of intersection of the other plate and the several parts then rigidly secured one to the other. It is not essential that the boom members 11 should extend downwardly and 50 rest upon the platform but, if desired, the triangular plates 26 may be relied upon to connect the boom with the platform itself. If the boom plates are terminated along the 55 upper edges of the triangular plates 26 then the plates 18 and 29 may be connected directly one to the other and rigidly secured to the lower edges of the boom members. The important feature of the construction 60 is the horizontal and vertical transverse reinforcing members arranged in intersecting planes and rigidly connected with the frame members and the boom plates or members.

The boom thus formed, while massive in construction, is of a compact arrangement, of relatively light weight as compared with its strength and of very great strength. The 65 parts thereof are rigidly braced and the

boom portion of the structure is so shaped and so reinforced and braced as to provide great strength at the points of strain. The straight line arrangement of the edges of the structure not only provides strength but 70 also tends to compactness and harmonious construction. While I have here shown and described the structure as formed of plates it will be obvious that this is not essential to the carrying out of the invention and 75 that lattice construction may, if desired, be employed, without material change in the design and arrangement of the structure as a whole.

While I have shown and described one embodiment of my invention I wish it to be understood that I do not desire to be limited to the details thereof as various modifications may appear to a person skilled in the art. 80

Having now fully described my invention, what I claim as new and desire to secure by Letters Patent, is:

1. In a boom structure of the character described, a frame portion comprising side 90 members having their upper edges inclined upwardly from the rear end thereof, a boom portion rigidly secured to said frame portion and extending upwardly and forwardly therefrom and having its lateral edges converging toward the point of the boom and arranged in line with the lateral edges of said side members. 95

2. In a boom structure, a frame portion comprising side members spaced apart, 100 tilted one toward the other and having their upper edges inclined from their rear ends to their free ends, and a boom portion rigidly secured to the forward end of said frame portion extending upwardly and forwardly therefrom and having its upper lateral edges arranged in line with the upper lateral edges of said side members, the lateral edges of said boom structure as a whole constituting straight lines extending from 110 the point of the boom to the rear end of the structure. 115

3. In a boom structure, a frame portion comprising upright side members having their lower edges substantially parallel and 120 having their upper edges inclined upwardly from their rear ends to their front ends, said side members being tilted one toward the other, a horizontal member arranged between and rigidly secured to said side members between the upper and lower edges thereof, and a boom portion rigidly secured to and extending upwardly and forwardly from said frame portion, the upper lateral edges of said boom portion converging toward the point of the boom and forming continuations of the upper lateral edges of the side members of said frame portion. 125

4. The combination with a supporting platform, of a boom structure comprising a 130

- frame portion consisting of side members mounted at their lower edges on said platform and converging upwardly therefrom, the upper edges of said side members being 5 inclined upwardly from the rear ends thereof to the forward ends thereof, bracing members connected with said side members, and a boom portion comprising parallel members resting at their rear ends on said 10 platform and extending upwardly and forwardly therefrom, said boom members being rigidly secured to said frame portion of said structure.
5. The combination with a supporting platform, of a boom structure comprising a frame portion having side members resting upon and extending upwardly from said platform and having their upper edges inclined from the rear end of said platform to 15 a point above the front end thereof, a boom portion comprising parallel members resting at their rear ends upon said platform and extending upwardly and forwardly therefrom, and transverse upright plates connecting said boom members with said side members.
6. The combination with a supporting platform, of a boom structure comprising a frame portion having side members extending upwardly from said platform, the upper edges of said side members being inclined upwardly from the rear end of said platform to a point above the front thereof, upright transverse members secured to 20 the respective side members and extending inwardly therefrom, said upright members having their inner edges spaced one from the other, a horizontal member rigidly secured to said upright members and to said side members, a boom portion comprising 25 longitudinal members extending between and rigidly secured to the edges of said upright members of said frame portion, the lower edges of said boom members resting upon said platform, an upright transverse member rigidly secured to the rear edges of said boom members and to said side members above the first mentioned upright transverse members, other horizontal members arranged substantially in line with the first 30 longitudinal members extending between and rigidly secured to the edges of said upright members of said frame portion, the lower edges of said boom members resting upon said platform, an upright transverse member rigidly secured to the rear edges of said boom members and to said side members above the first mentioned upright transverse members, other horizontal members arranged substantially in line with the first 35 horizontal member and rigidly secured at their edges to the respective boom members and upright members, and a triangular plate arranged on each side of said boom portion, rigidly secured at their upper edges to the respective boom members along the edges of the last mentioned horizontal members and extending downwardly and outwardly therefrom, and rigidly secured at their rear edges to the first mentioned upright transverse members.
7. The combination with a supporting platform, of a boom structure comprising a frame portion having side members extending upwardly from said platform, the upper edges of said side members being inclined upwardly from the rear end of said platform to a point above the front thereof, upright transverse members secured to the respective side members and extending inwardly therefrom, said upright members having their inner edges spaced one from the other, a horizontal member rigidly secured to said upright members and to said side members, a boom portion comprising 40 longitudinal members extending between and rigidly secured to the edges of said upright members of said frame portion, the lower edges of said boom members resting upon said platform, and an upright transverse member rigidly secured to the rear ends of said boom members and to said side members above the first mentioned upright transverse member.
8. The combination with a supporting platform, of a boom structure comprising a frame portion having side members extending upwardly from said platform, the upper edges of said side members being inclined upwardly from the rear end of said platform to a point above the front thereof, upright transverse members secured to the respective side members and extending inwardly therefrom, said upright members having their inner edges spaced one from the other, a horizontal member rigidly secured to said upright members and to said side members, a boom portion comprising 45 longitudinal members extending between and rigidly secured to the edges of said upright members of said frame portion, the lower edges of said boom members resting upon said platform, an upright transverse member rigidly secured to the rear edges of said boom members and to said side members above the first mentioned upright transverse members, other horizontal members arranged substantially in line with the first horizontal member and rigidly secured at their edges to the respective boom members and upright members, and a triangular plate arranged on each side of said boom portion, rigidly secured at their upper edges to the respective boom members along the edges of the last mentioned horizontal members and extending downwardly and outwardly therefrom, and rigidly secured at their rear edges to the first mentioned upright transverse members.
9. The combination with a supporting platform, of a boom structure comprising side plates extending upwardly from said platform and having their upper edges inclined upwardly and forwardly, bracing members rigidly secured to the inner faces of said side plates, a horizontal plate extending between and rigidly secured to said side plates between the upper and lower edges thereof, and parallel plates resting at their rear edges on said platform and having their respective upper and lower edges converging away from said platform, bracing members rigidly secured to the outer edges of said parallel plates, and transverse upright plates rigidly connected with said parallel plates and with said side plates.
10. The combination with a supporting platform, of a boom structure comprising 50

side plates converging upwardly from said platform and having their upper edges inclined upwardly and forwardly, brace members secured to and extending inwardly from the respective side plates, upright transverse plates rigidly secured to the forward edges of said side plates and extending inwardly therefrom, said upright plates having their inner edges spaced apart, a horizontal plate rigidly secured at its respective edges to said side plates and to said upright plates, parallel plates having their rear edges extending between said upright plates, resting upon said platform and having their respective upper and lower edges converging away from said upright plates, bracing members rigidly secured to the outer surfaces of the respective parallel plates and extending outwardly therefrom, a second upright plate rigidly secured to the rear ends of said parallel members above the first mentioned upright plates and secured at its edges with said side plates, and a top plate rigidly secured to the upper edges of said side plates, said parallel plates and said bracing members, and having each lateral edge constituting a straight line from one end of said structure to the other.

11. The combination with a supporting platform, of a boom structure comprising side plates converging upwardly from said platform and having their upper edges inclined upwardly and forwardly, brace members secured to and extending inwardly from the respective side plates, upright transverse plates rigidly secured to the forward edges of said side plates and extending inwardly therefrom, said upright plates having their inner edges spaced apart, a horizontal plate rigidly secured at its respective edges to said side plates and to said upright plates, parallel plates having their rear edges extending between said upright plates, resting upon said platform, and having their respective upper and lower edges converging away from said upright plates, bracing members rigidly secured to the outer surfaces of the respective parallel plates and extending outwardly therefrom, a second upright plate rigidly secured to the rear ends of said parallel members above the first mentioned upright plates and secured at its edges to said side plates, other horizontal plates arranged on the opposite sides of said parallel plates in substantially the same plane with the first mentioned horizontal plate and rigidly secured to the respective parallel plates and upright plates, and triangular plates secured at their upper edges to the respective parallel plates along the inner edges of the last mentioned horizontal plates and having their rear edges secured to the first mentioned upright plates and extending diagonally thereof.

12. The combination with a supporting platform, of a boom structure comprising side plates converging upwardly from said platform and having their upper edges inclined upwardly and forwardly, brace members secured to and extending inwardly from the respective side plates, upright transverse plates rigidly secured to the forward edges of said side plates and extending inwardly therefrom, said upright plates having their inner edges spaced apart, a horizontal member rigidly secured at its respective edges to said side plates and to said upright plates, parallel plates having their rear edges extending between said upright plates, resting upon said platform, and having their respective upper and lower edges converging away from said upright plates, bracing members rigidly secured to the outer surfaces of the respective parallel plates and extending outwardly therefrom, a second upright plate rigidly secured to the rear ends of said parallel plates above the first mentioned upright plates and secured at its edges to said side plates, other horizontal plates arranged on the opposite sides of said parallel plates in substantially the same plane with the first mentioned horizontal plate and rigidly secured to the respective parallel plates, and upright plates, and a top plate secured to the upper edges of said parallel plates and the bracing members therefor and having its lateral edges arranged in line with the upper edges of the respective side plates.

13. The combination with a supporting platform, of a boom structure comprising

side plates converging upwardly from said platform and having their upper edges inclined upwardly and forwardly, brace members secured to and extending inwardly from the respective side plates, upright transverse plates rigidly secured to the forward edges of said side plates and extending inwardly therefrom, said upright plates having their inner edges spaced apart, a horizontal member rigidly secured at its respective edges to said side plates and to said upright plates, parallel plates having their rear edges extending between said upright plates, resting upon said platform, and having their respective upper and lower edges converging away from said upright plates, bracing members rigidly secured to the outer surfaces of the respective parallel plates and extending outwardly therefrom, a second upright plate rigidly secured to the rear ends of said parallel members above the first mentioned upright plates and secured at its edges to said side plates, other horizontal plates arranged on the opposite sides of said parallel plates in substantially the same plane with the first mentioned horizontal plate and rigidly secured to the respective parallel plates and upright plates, and triangular plates secured at their upper edges to the respective parallel plates along the inner edges of the last mentioned horizontal plates and having their rear edges secured to the first mentioned upright plates and extending diagonally thereof.

14. The combination with a supporting platform, of a boom structure comprising side plates converging upwardly from said platform and having their upper edges inclined upwardly and forwardly, brace members secured to and extending inwardly from the respective side plates, upright transverse plates rigidly secured to the forward edges of said side plates and extending inwardly therefrom, said upright plates having their inner edges spaced apart, a horizontal member rigidly secured at its respective edges to said side plates and to said upright plates, parallel plates having their rear edges extending between said upright plates, resting upon said platform, and having their respective upper and lower edges converging away from said upright plates, bracing members rigidly secured to the outer surfaces of the respective parallel plates and extending outwardly therefrom, a second upright plate rigidly secured to the rear ends of said parallel plates above the first mentioned upright plates and secured at its edges to said side plates, other horizontal plates arranged on the opposite sides of said parallel plates in substantially the same plane with the first mentioned horizontal plate and rigidly secured to the respective parallel plates and upright plates, and triangular plates secured at their upper edges to the respective parallel plates along the inner edges of the last mentioned horizontal plates and having their rear edges secured to the first mentioned upright plates and extending diagonally thereof.

edges to the respective parallel plates along the inner edges of the last mentioned horizontal plates and having their rear edges secured to the first mentioned upright plates 5 and extending diagonally thereof, and a top plate secured to said parallel members and the brace members therefor and having its lateral edges in line with the upper edges of the respective side plates.

10 14. The combination with a supporting platform, of a boom structure comprising triangular side plates supported at their lower edges on said platform and converging upwardly therefrom, brace plates rigidly secured to and extending inwardly from said triangular plates, top plates secured to the upper edges of the respective side members and the adjacent brace plates, upright plates secured to the forward edges of said 20 side plates and extending inwardly therefrom, the inner edges of said upright plates being spaced apart, a horizontal plate rigidly secured at its edges to said side plates and the upper portions of said upright 25 plates, a pair of parallel boom plates extending between the edges of said upright plates and resting upon said platform, an upright plate rigidly secured to the ends of said boom plates above the first mentioned 30 upright plates and rigidly secured at its edges to said side plates, transverse bracing plates rigidly secured to said respective boom plates and extending outwardly therefrom, horizontal plates rigidly secured to 35 the respective boom plates in substantially the same plane as the first mentioned horizontal plate and secured at their rear edges to the respective first mentioned upright plates, triangular plates secured along their 40 upper edges to the respective boom plates along the inner edges of the last mentioned horizontal plates and secured at their rear edges to the first mentioned upright plates along diagonal lines, and a top plate extending for the full length of said boom 45 structure and secured to the upper edges of said boom plates and the several bracing plates therefor, and forming a continuation of the first mentioned top plates, the 50 lateral edges of said top plate each constituting a straight line for the full length of said boom structure.

15. In a structure of the character described, a platform, side members extending upwardly from said platform near the respective lateral edges thereof, a transverse upright member secured at its edges to said side members near the forward edges of the latter, substantially parallel upright members secured at their rear edges to said transverse member and extending upwardly and forwardly therefrom, and a transverse horizontal member rigidly secured to said side members and to said transverse member.

65 16. In a structure of the character de-

scribed, a platform, side members extending upwardly from said platform near the respective lateral edges thereof, a transverse upright member secured at its edges to said side members near the forward edges of the latter, substantially parallel upright members secured at their rear edges to said transverse member and extending upwardly and forwardly therefrom, a transverse horizontal member secured at its lateral edges to said side members and at its forward edge to said transverse member, and a transverse horizontal member arranged substantially in line with the first mentioned horizontal member and secured at its rear edge to said upright transverse member and extending lengthwise of and secured to one of said parallel upright members.

17. In a structure of the character described, a platform, side members extending upwardly from said platform near the respective lateral edges thereof, a transverse upright member secured at its edges to said side members near the forward edges of the latter, substantially parallel upright members secured at their rear edges to said transverse member and extending upwardly and forwardly therefrom, a transverse horizontal member rigidly secured at its lateral edges to said side members and at its forward edge to said transverse member, and transverse horizontal members arranged substantially in line with the first mentioned horizontal member and secured at their rear ends to said transverse upright member and secured at their lateral edges to the respective parallel upright members.

18. In a structure of the character described, a platform, side members extending upwardly from said platform near the respective lateral edges thereof, a transverse upright member secured at its edges to said side members near the forward edges of the latter, substantially parallel upright members secured at their rear edges to said transverse member and extending upwardly and forwardly therefrom, a transverse horizontal member rigidly secured at its lateral edges to said side members and at its forward edge to said transverse member, transverse horizontal members arranged substantially in line with the first mentioned horizontal member and secured at their rear ends to said transverse upright member and secured at their lateral edges to the respective parallel upright members.

19. In a structure of the character described, a platform, side members extending upwardly from said platform near the re-

spective edges thereof, transversely extending horizontal and vertical members arranged in intersecting planes and rigidly connected with said side members, and parallel upright members rigidly secured to said horizontal and said vertical members and extending upwardly and forwardly therefrom.

20. In a structure of the character described, a platform, side members extending upwardly from said platform near the respective edges thereof, transversely extending horizontal and vertical members arranged in intersecting planes and rigidly connected with said side members, parallel

upright members rigidly secured to said horizontal and said vertical members and extending upwardly and forwardly therefrom, said upright parallel members being spaced apart a distance less than the distance between said side members, and members rigidly secured to the respective upright parallel members extending downwardly and outwardly therefrom and rigidly connected at their rear edges with said vertical transverse member. 20

In testimony whereof, I affix my signature hereto. 25

GRANT HOLMES.
